INVENTOR,
EUGENE CURRIE
BY HIS ATTORNEYS.

Williamson & Williamson

UNITED STATES PATENT OFFICE

EUGENE CURRIE, OF MINNEAPOLIS, MINNESOTA

SANITARY BRUSH

Application filed April 8, 1932. Serial No. 603,967.

My invention relates to brushes and particularly to a sanitary brush for use by barbers and the like.

Brushes are commonly used by barbers for applying powder to the face and neck and for removing hair clippings from the face and neck. Brushes ordinarily used for this purpose are very unsanitary. In some cases, to avoid unsanitary conditions, after a brush is used on one patron it is cleansed and sterilized for subsequent use. With this system, which requires a great number of brushes, the investment in brushes and the cost of cleansing and sterilizing are considerable.

An object of my invention is to provide a brush of the class described comprising a handle and a quickly and easily replaceable head or bristle portion.

A further object of my invention is to provide a brush of the class described which is very simple and inexpensive of manufacture.

A still further object is to provide a brush of the class described wherein the bristle portion may be made of paper or other suitable inexpensive sheet material.

These and other objects and advantages of the invention will be more fully set forth in the following description made in connection with the accompanying drawing, in which like reference characters refer to similar parts throughout the several views, and in which:—

Fig. 1 is a side view of my brush partially broken away to more clearly show the relation between the parts thereof;

Fig. 2 is a transverse cross sectional view of my brush taken along the line 2—2 of Fig. 1 as indicated by the arrows;

Fig. 3 is a view of the folded paper blank from which the bristle portion of my brush is formed;

Fig. 4 is a cross sectional view of the folded paper blank taken along the lines 4—4 of Figs. 3 as indicated by the arrows;

Fig. 5 is a partially broken away side view of the cup-shaped member in which the bristle portion is secured, and which is part of the removable portion of the brush, and

Fig. 6 is a view of a portion of the folded

paper blank from which the bristle portion of a modified form of my brush is made.

Referring to the drawing, a rectangular sheet 7, of paper or other suitable sheet material, is folded along its longitudinal center line in such manner that the halves thereof, at the two sides of said line, extend from the fold parallel to each other. Each half of the folded sheet 7 is transversely slit from the free edge thereof toward the folded edge to form a series of narrow bristle-like strips 8, the slit portion thereof terminating short of the folded edge. The folded sheet is then tightly rolled so that the unslit portion 9, adjacent the folded edge thereof, will form a cylindrical body 9a with the bristle-like strips depending therefrom. Preferably the convolutions of the body 9a will be glued or otherwise secured together. A shallow cup 10, formed of metal or other suitable material, is slid onto the cylindrical body and is secured thereon by means of glue or cement or by other suitable means. A handle, preferably made of wood or similar material, is provided at one end with an enlarged portion 11a, having in the end thereof a recess 11b in which the outer periphery of the cup 10 is frictionally engaged. The cup 10 is so proportioned that the outer periphery thereof will engage the interior periphery of the recess 11b with such a degree of tightness that said cup can be resistively drawn from or inserted in said recess, but will not drop out of said recess. The enlarged portion 11a is beveled at the outer end of the recess 11b to assist in centering the cup 10 when inserting the same in the recess.

In the modified form of my brush, the construction and assembly of the same are identical with that of the form described above with the exception that the free ends of the bristle like strips 12 are rounded, as shown in Figure 6.

When my brush is used by barbers and the like, the bristles 8, body 9a, and cup 10, as a unit, are replaced for sanitary reasons after the same has been used on a patron. The handle portion 11 obviously is retained and used with many successive brush units.

It is apparent that I have invented a new and useful form of sanitary brush wherein the bristle portion can be very quickly and easily replaced and in which the handle portion may be used repeatedly. It is also apparent that my brush as a whole, and the replaceable bristle portion in particular, is very simple and inexpensive of manufacture.

10 It is obvious that my brush structure is readily adaptable to brushes of various sizes and for various purposes and that the bristle portion may be made of any suitable sheet material. It is also apparent that the slit 15 paper blank, from which the bristles of my brush are formed, may be formed into a brush by other methods than rolling, such as, for example, by folding similar to the form of folding employed in forming accordion 20 pleats.

It will, of course, be understood that various changes may be made in the form, details, proportions and arrangement of the parts, without departing from the scope 25 of my invention, which, generally stated, consists in a device capable of carrying out the objects above set forth and in the novel parts and combinations of parts disclosed and defined in the appended claims.

30 What is claimed is:—

1. A method of constructing a brush head in which a rectangular sheet of material is first folded along the longitudinal center line thereof, the portions adjacent the fold being 35 disposed parallel to and substantially in contact with each other, said folded sheet is then slit transversely from the free edges of said portions thereof toward the folded edge to form a series of narrow, bristle-like 40 strips, the corners are removed from the free ends of said strips, said folded and slit sheet is rolled to form a cylindrical bristle structure, and means is applied adjacent the end formed by said folded edge to retain said 45 structure in rolled form.

2. A method of constructing a brush head in which a rectangular sheet of material is first folded along the longitudinal center line thereof, the portions adjacent the fold being 50 disposed parallel to and substantially in contact with each other, said folded sheet is then slit transversely from the free edges of said portions thereof toward the folded edge to form a series of narrow bristle-like strips, 55 the free ends of said strips are rounded, said folded and slit sheet is rolled to form a cylindrical bristle structure, and means is applied adjacent the end formed by said folded edge to retain said structure in rolled form.

60 In testimony whereof I affix my signature.

EUGENE CURRIE.
